UNITED STATES PATENT OFFICE.

HENRY ROBINSON, OF SOUTH ORANGE, NEW JERSEY.

DESIGN FOR A FRAME FOR KNIFE-POLISHING MACHINES.

49,623.

Specification for Design.

Patented Sept. 5, 1916.

Application filed March 3, 1916. Serial No. 82,005. Term of patent 7 years.

To all whom it may concern:

Be it known that I, HENRY ROBINSON, a citizen of the United States, and a resident of South Orange, in the county of Essex and State of New Jersey, have invented a new, original, and ornamental Design for Frames for Knife-Polishing Machines, of which the following is a specification, reference being had to the accompanying drawing, forming a part thereof.

Figure 1 is a top plan view of a frame embodying my invention; Fig. 2 is a side elevation; and Fig. 3 is a front view.

I claim:

The ornamental design for a frame for a knife polishing machine, as shown.

HENRY ROBINSON.

Witness:

GEO. C. BURBANK.
